UNITED STATES PATENT OFFICE.

JOHN S. CLARKE, OF EAST CHINA, ASSIGNOR OF ONE-HALF TO JOSEPH FRANK DUNNEBACK, OF DETROIT, MICHIGAN.

FEED-WATER REGULATOR.

SPECIFICATION forming part of Letters Patent No. 276,355, dated April 24, 1883.

Application filed August 24, 1882. (No model.)

To all whom it may concern:

Be it known that I, JOHN S. CLARKE, of East China, in the county of St. Clair and State of Michigan, have invented a new and Improved Feed-Water Regulator and Alarm for Steam-Boilers, of which the following is a full, clear, and exact description.

My invention consists of a waste-pipe connected with the feed-water pipe from the pump 10 to the boiler, together with a valve to open said pipe and allow the water from the pump to escape when the boiler is full, and to close it and cause the water to enter the boiler when required, the said valve being controlled by a 15 float in the boiler, which float is also made to cause a whistle to sound an alarm in case the pump, injector, or inspirator fails to act and the water falls too low in the boiler, all as hereinafter fully described.

Reference is to be had to the accompanying drawing, forming part of this specification, in which drawing is shown a sectional elevation of my improved feed-water regulator and alarm apparatus.

The feed-water pipe *a*, leading from the pump (not shown) to the boiler *b*, to which it is to be connected in any approved manner, has a branch, *c*, connected to it between the pump and the boiler, with a double valve, *d e*, in it, 30 to the part *e* of which steam is to be admitted from the boiler through pipe *f* by a float, *g*, and valve *h*. When the water in the boiler allows the float to fall, the steam, pressing on part *e*, which is larger than part *d*, which controls the waste-passage, will close the waste-pipe by the greater pressure on said part *e*, causing the water to be forced into the boiler by the pump. When the water rises in the boiler so that float *g* will close valve *h* and 35 shut the steam off from valve *e*, the water from the pump will escape through the waste-pipe *c*. A check-valve, properly located in pipe *a*, between the waste-pipe connection and the boiler, will prevent the escape of water from 40 the boiler through the waste-pipe.

The float *g* is made hollow for buoyancy, and it is provided with a tubular rod, *i*, which

opens to the atmosphere outside of the boiler for the escape of any vapor that may be caused in the float from water entering it 50 through the pores of the metal, which would ultimately fill it and render it useless.

The valve *h* is balanced to make it open readily, and care is to be taken to so construct it that it will not stick fast in any case; but 55 for greater safety the rod *i* of the float is fitted through the arm *j* of the valve-rod of an alarm-whistle, so that in case the pump, injector, or inspirator fails for any cause and the water falls too low the collar *l* on the rod *i* will open 60 the valve *m* of the whistle *k* and sound the alarm.

n represents a tubular guard, extending down within the boiler to support the float-rod against lateral thrusts of the float by the 65 waves or currents of water set in action by the heat.

The valve *h* is arranged in a casting, *o*, which is attached to the dome *p* of the boiler by any suitable connecting-nipple, *q*, into the lower 70 end of which the guard *n* is screwed, the nipple having a reducer, *s*, in the lower end, which may have perforations *t* for the passage of the steam, the guard *n* being closed at the lower end for a support to the rod *i*.

Having thus described my invention, what I claim as new, and desire to secure by Letters Patent, is—

1. The combination of the float *g*, balanced valve *h*, double valve *d e*, steam-pipe *f*, feed-water pipe *a*, and the waste-pipe *c*, substantially as described.

2. The combination, with the feed-water pipe *a*, boiler-steam pipe *f*, and waste-pipe *c*, of the connected relief-valves *d e*, arranged as 85 and for the purpose specified.

3. The combination, with the boiler-dome *p*, of the nipple *q*, having guard *n*, reducer *s*, and perforations *t*, as shown and described.

JOHN S. CLARKE.
